COVER DEVICE

Virgilius Joseph Braun, Los Angeles, Calif., assignor, by
mesne assignments, to Hughes Aircraft Company, a
corporation of Delaware

Application January 19, 1953, Serial No. 332,030

2 Claims. (Cl. 135—5)

This invention relates generally to means for protecting articles or their contents, and more particularly to a spring-like, self-releasing cover device suitable, for example, for providing a protective covering for an article, and which is capable of being easily removed from the article with a minimum amount of handling and damage to the article. 15

Cover devices, as employed heretofore, generally require some application of force to remove them, and the transfer of such force to the article itself may damage the article. Such damage to the article may represent a considerable loss of time and investment. 20

This invention provides a protective cover device which requires a minimum of handling to release it from an article and which permits the use of protective coverings having characteristics desired for optimum protection for the particular article to be covered. In accordance with one embodiment of this invention, the cover device includes a hub member from which a plurality of spoke-like, flexible rod members extend. The outer ends of the rods are flexed, in the same direction, toward the axis of the hub member, and they are maintained in the flexed position by a suitable banding element, which may be wire cord, or a fiber strap, that engages the ends thereof. A covering material such as paper or foil surrounds the hub member and rods to provide a bag-like protecting cover to be placed over the article. When it is desired to remove the cover, the banding element may be parted, as by being broken or cut, to free the flexed rods for movement away from the axis of the hub member. The rods are adapted to spring from their flexed positions and lift or fold the covering material therewith. Subsequently, the entire assembly may be lifted away from the exposed article. 30

It is, therefore, an object of this invention to provide an improved covering device for protecting articles and/or their contents, in which a covering material surrounds spring-like elements held in flexed condition, and in which such spring-like elements may be freed to unflex and provide for easy removal of the covering material from the article. 45

It is another object of this invention to provide an improved cover device which may surround an article to be protected, and which requires a minimum of handling for removal thereof from the article. 50

It is still a further object of this invention to provide an improved cover device for protecting articles which employs a minimum number of inexpensive component parts of simple design and which is capable of reliable operation. 60

The novel features which are believed to be characteristic of the invention, both as to its organization and method of operation, together with further objects and advantages thereof, will be better understood from that following description considered in connection with the accompanying drawing, in which preferred embodiments of the invention are illustrated by way of example. The 65

2

scope of the invention is pointed out in the appended claims. Referring to the drawing:

Fig. 1 is a top plan view of the skeletal structure of a cover device in accordance with this invention; 5

Fig. 2 is a view in elevation, with certain parts being broken away, of a cover device utilizing the skeletal structure of Fig. 1;

Fig. 3 is a view in elevation, parts being broken away, of a second embodiment of the cover device shown in Fig. 2 for use as a covering for bottles, also in accordance with this invention; 10

Fig. 4 is a perspective view illustrating still another embodiment of the cover device of the invention shown in Fig. 2 to provide a very simple but effective protective covering for the protection of small plants; and 15

Fig. 5 is a perspective view showing the skeletal structure of the protective cover device shown in Fig. 4 after removal of the covering. 20

Referring to the drawing, in which like reference characters indicate like parts throughout, and more particularly to Figs. 1 and 2, the cover device of this invention employs a skeletal structure comprising a central member or hub 10. Spaced about the periphery of the hub in spoke-like fashion are a number of flexible rods 12. The inner ends of these rods are secured in the lateral peripheral surface of the hub 10. Spaced a short distance from the outer end of each rod is a depression or recess 14 which, as will now be explained with reference to Fig. 2, provides means for securing the rods 12 in a flexed condition. 25

As shown in Fig. 2, the rods 12 have their ends pulled inward toward the axis of the hub 10. They are maintained in this flexed position by a banding element, such as a strap or wire 16 which surrounds all the rods 12. 30 To insure that rods 12 will be held flexed, the banding wire 16 may thread through loops formed by the rods 12 adjacent their ends, or, as shown in Fig. 2 the banding wire 16 may rest in depressions 14 at the outer ends of rods 12. The banding wire 16 has its ends connected by a suitable connecting link member 18. Surrounding the rods 12, and extending from the hub 10 substantially to the ends of the rods 12, is a suitable cover or covering material 20 for enclosing and protecting an article. 35

In the present embodiment of this invention, the cover device is placed over an article, as schematically indicated at 22. The banding wire 16, which is placed over the rods 12 and covering material 20, is drawn tight

so as to secure the rods 12 and covering material 20 tightly about the article 22. In this manner, a suitable 40

dust-tight covering for the article 22 is provided. When it is desired to remove such covering from the device 22, the mechanical connection between the ends of the banding wire 16, as provided by the connecting link 18, may be broken. The manner of breaking such mechanical 45

connection may, of course, be manual, that is, the connecting link 18 may be cut with a suitable implement. However, the connecting link 18, in addition to providing 50

sufficient mechanical strength to hold the flexed rods 12 securely to the article 22, may comprise a conductive fuse 55

element adapted for connection, as indicated, to a suitable control circuit 24. Upon sufficient current being supplied from control circuit 24 to weaken such fuse, the outward force of the flexed rods 12 against the banding wire 16 will cause the connecting link 18 to break. 60

Upon the mechanical linkage provided by connecting link 18 being broken, the rods 12 are adapted to disengage the article 22 by folding back covering material 20 and tending to assume a position in the plane of the hub 10 (Fig. 1). The material 20 may have folds so that it 65

will readily unfold upon the rods 12 unflexing, or the material 20 may be thin and drawn tightly over the rods 70

12, whereupon the unflexed rods may tear through it. The cover device may then be removed with ease, as, for example, by lifting away from the article 22 by means of a small ring 26 affixed to the top of the hub 10.

The covering material 20 provided for the cover device of this invention may comprise material suitable for the protection required for the article 22. For example, if the article 22 requires only that protection which can be provided by untreated paper, the covering material 20 may be comprised of such untreated paper. On the other hand, covering material 20 may be exposed to the atmosphere, and it may be desirable that it be substantially weatherproof; in this case, suitably treated material may be used as the covering material 20.

The article 22 to be protected may comprise electronic parts which may be susceptible to injury, or whose efficiency may be damaged, by strong radiant energy signals in the vicinity thereof. The covering material 20, to be adequate for proper protection of an article 22 of this character, may comprise material that is capable of reflecting and/or absorbing radiant energy, such as aluminum foil of adequate thickness.

An adaptation of the cover device of the invention for use in the bottling industry is illustrated in Fig. 3. Referring to Fig. 3, a bottle, as indicated at 30, is adapted to be corked by means of a cover device utilizing a hub member in the form of a cap 32 for a cork or stopper 34. The cap 32 serves the same purpose as the hub 10 of Figs. 1 and 2, and flexible rods 12 are attached thereto in the same manner. Upon the cork 34 being placed in the neck of the bottle 30, the ends of the flexible rods 12 may be forced downwardly over the neck of the bottle 30, where they are secured in position by the use of banding wire 16 and connecting link 18 in the manner previously described. The covering material 20 in this case may be any suitable covering material used in the industry, such, for example, as metal foil. The ends of the rods 12 may be rounded, as shown, so they can be gathered by hand to remove the cork 34 from the bottle 30; alternatively, a ring, such as ring 26 of Fig. 1, may be provided for removing cork 34.

Another adaptation of the cover device of the invention heretofore described for use in the agricultural field is illustrated in Figs. 4 and 5. In the agricultural field, extended use of paper bags, known as "hot caps," is made for protecting young plants during an initial critical period of growth. Heretofore, it has been the practice to cover individual plants with such a paper bag, firmly packing dirt around the open end of the paper bag to hold it to the ground, and relying upon the elements to effect deterioration of the paper at the end of such critical period of growth. Among the problems presented by the use of such protective coverings is that of non-uniform deterioration of the paper. In many instances, partially deteriorated paper may be blown against the plant and injure it. In other instances, deterioration may not be sufficiently rapid to free the plant from its covering so as to permit it to receive sufficient air and sunlight to further promote its growth. In such instances, vigil must be exercised to discover faulty coverings, and they must be removed by hand from the plants. The use of the protective covering device of this invention to avoid such losses of investment will now be explained.

Referring to Fig. 4, a small hub member 40 is shown supporting four flexible rods 42, 43, 44, 45 of the type previously described. As shown, two of the rods 44, 45, which are placed relatively close together, are longer than the other rods 42, 43. In this embodiment of the invention, the rods 42, 43, 44, 45 preferably are held flexed only by the covering material 46 that surrounds them. Covering material 46 extends from the hub member 40 to a plane passing through the ends of the shorter rods 42, 43. Projecting portions of the longer rods 44, 45 constitute prongs 47, 48 which, for example, may be inserted in the ground for holding the cover device in a

desired position. As employed for the protection of young plants, the covering material 46 may be placed over the plant and the prongs 47, 48 inserted in the ground for anchoring the cover device over the plant.

The covering material 46 preferably is chemically treated so that it will begin to deteriorate at the end of the desired period through which protective covering for a plant is required. At the termination of such critical period, upon weakening of the covering material 46, the flexed rods 42, 43 will tear through the covering material 46 and away from the plant thereunder. The covering material 46 will thus be torn and lifted away from the plant, thereby permitting air and sunlight to reach the plant for furthering its growth. The removed covering may thus complete its deterioration without injury to the plant and loss of investment therein.

Fig. 5 illustrates the position of the hub member 40 and rods 42, 43, 44, 45 following the removal of the covering material 46 from a plant in the manner above described. The longer rods 44, 45 will, of course, have remained in the ground to provide a pivot around which the hub member 40 and the shorter rods 42, 43 unflex. It is to be noted that the skeletal structure provided by such hub member 40 and the rods 42, 43, 44, 45 is a salvageable article, because it may be removed from the ground and recovered, thereby permitting its repeated use for the same purpose.

With reference to the flexible rods 12 (Figs. 1-3) and 42, 43, 44, 45 (Figs. 4 and 5), they may be made of any suitable material. For example, such rods may be formed of suitable metals, such as Phosphor bronze, or they may be formed of suitable plastic material adapted to be flexed and which has spring-like qualities.

From the foregoing, it is clear that there has been described an improved cover device for articles, in which self-releasing elements are provided for permitting easy removal of such device from an article with a minimum of handling and possible abuse of the article.

What is claimed is:

1. A cover device adapted for disposition over articles to be protected comprising, in combination: a hub member; a plurality of flexible rods cylindrical in cross section, having ends thereof secured to a peripheral portion of said hub member and normally biased for disposition radially outwardly therefrom, said rods being adapted for flexation to establish a generally conical frame structure; laterally disposed notches in each of said rods adjacent free ends thereof remote from said secured ends; an unsecured protective cover positioned on said rods, said cover having a configuration conforming to said generally conical frame structure established by said rods; a resilient banding member having free ends disposed about said protective cover and overlying said notches in said rods for maintaining said rods in a flexed position and securing said cover thereto; and an electrically fusible link connected to said ends of said banding member for maintaining said ends together, said rods being adapted for flexation toward said normal radial position thereof upon fusion of said link to effect removal of the cover and rods from said article being protected.

2. A cover device according to claim 1 wherein said protective cover is of frangible, radiantly reflective material and adapted to tear away upon said flexation of said rods toward said normal position thereof.
